[57] CLAIM

The ornamental design for a combined cover and basket support for small machinery parts cleaner, as shown and described.

DESCRIPTION

FIG. 1 is a top plan view of a combined cover and basket support for small machinery parts cleaner showing my new design;

FIG. 2 is a bottom view thereof;

FIG. 3 is a side elevational view looking in the direction of the arrows 3—3 of FIG. 1 showing a basket for machinery parts in dotted lines for illustration purposes only, the side not shown being identical to the side shown; and,

FIG. 4 is a side elevational view looking in the direction of the arrows 4—4 of FIG. 1, the side not shown being a mirror image of the side shown.

FIG. 1

FIG. 4
